United States Patent Office

Des. 184,083
Patented Dec. 16, 1958

184,083

BOTTLE CAP

Lindsay T. Crabbe, Hinsdale, Ill., assignor to Phoenix Metal Cap Co., Chicago, Ill.

Application March 8, 1957, Serial No. 45,170

Term of patent 14 years

(Cl. D58—26)

FIG. 1.

FIG. 2.

Fig. 1 is a top plan view of a bottle cap showing my new design; and

Fig. 2 is a side elevation thereof.

The side of the cap not shown is the same as the side illustrated.

I claim:

The ornamental design for a bottle cap, as shown and described.
